(57) **CLAIM**

I claim the ornamental design for a snuff container lid, as shown and described.

DESCRIPTION

FIG. 1 is an enlarged top perspective view of the snuff container lid according to the new design;

FIG. 2 is a top perspective view thereof;

FIG. 3 is a top view of FIG. 2; and,

FIG. 4 is an exploded perspective view thereof.

The broken lines are shown for illustrative purposes only and form no part of the claimed design.

1 Claim, 3 Drawing Sheets
